SIGNALING SYSTEM

Lloyd V. Lewis, Edgewood, Pa., assignor to The Union Switch & Signal Company, Swissvale, Pa., a corporation of Pennsylvania

Application April 5, 1935, Serial No. 14,863

14 Claims. (Cl. 246—2)

My invention relates to signaling systems for railroads, and more particularly, to systems in which control signals are transmitted from a sending station to a remote receiving station.

5 One object of my invention is the provision, in a system of this character, of means for storing a plurality of signals at the receiving station and for cancelling these one at a time when acted upon.

10 The specific object of the forms of my invention herein illustrated and described, is the provision of a system for indicating the routes to be taken by vehicles successively approaching a junction point for diverging routes, in which the 15 route indications are registered in advance and in which each route indication is stored until the corresponding vehicle passes the junction point.

10 The apparatus of my invention is an improvement upon that disclosed in an application of 20 Paul Abelos, Serial No. 699,798, filed November 25, 1933, for Automatic selection station, and is also an improvement upon that disclosed in an application of Ralph Mordin, Serial No. 85,544, 25 filed June 16, 1936, for Remote control apparatus.

I will describe two forms of apparatus embodying my invention, and will then point out the novel features thereof in claims.

20 In the accompanying drawings, Fig. 1 illustrates a route indicating system embodying my invention in which the route indications are registered by means of a visual indicator provided for the guidance of a local operator or leverman, and in which the registered indications are released manually. Fig. 2 illustrates another form 30 of my invention in which a track switch is operated automatically in accordance with the route indications, and in which the indications are released automatically as the vehicles successively 35 pass over the switch.

40 Similar reference characters refer to similar parts in the two views.

45 Referring first to Fig. 1, the diagram at the top represents a stretch of track over which railway cars or trains move from point *a* to point *b*, and thence over the track switch *W* to point *x* or to point *y*, according to the position of the track switch. Switch *W* is controlled by an operator or leverman stationed in a nearby signal tower *D*, 50 who is kept informed as to the routes to be taken by approaching trains by means of indication lamps contained in a track model *V*, the lamps being controlled through the medium of the relays shown in the drawings by the operation of keys 55 or push buttons contained in a control panel *U*.

The control panel may be located in the dispatcher's office, or at a station *O* adjacent point *a*, where it may be operated either by an operator stationed at that point or by the crews of passing trains, as desired. The apparatus at tower *D* 5 includes a plurality of indicators arranged in groups comprising pairs of lamps designated *XE*¹ and *YE*¹, *XE*² and *YE*², etc., which are selectively controlled by the relays in response to repeated operation of the keys of the control panel *U* to 10 indicate the routes to be taken by the successive trains. That is, a first operation of key *KX* or *KY* will light lamp *XE*¹ or *YE*¹, of the first indicator, to indicate that the first train is to move to point *x* or to point *y*, respectively; a second 15 operation will light lamp *XE*² or *YE*², of the second indicator to similarly indicate the route to be taken by the next following train, while a third operation will light lamp *XE*³ or *YE*³ of the last indicator. As each train passes switch 20 *W*, the corresponding route indication displayed by lamp *XE*¹ or *XE*² of the first indicator is cancelled by the operator at tower *D* by momentarily operating a release key *KD* associated with track model *V*. When key *KD* is released, the 25 indication stored in the second indicator is transferred to the first so that lamp *XE*¹ or *YE*¹ becomes lighted in accordance with the indication which was previously stored in the second indicator and the second indicator then releases. The 30 indication stored in the third indicator thereupon is transferred to the second and the third indicator releases. The first and second indicators will now indicate the respective routes to be taken by the two trains remaining in the 35 stretch *a*—*b*. The keys of the control panel *U* may now be actuated again to operate the third indicator to register the route to be taken by a following train. The route indications are thus 40 registered in sequence as the trains enter the stretch, and the stored indications move step-by-step through the indicators of the track model in response to the repeated operation of key *KD* as the trains move through stretch *a*—*b* and pass switch *W*.

45 Each pair of indication lamps is controlled by a pair of stick relays bearing corresponding references such as relays *X*¹ and *Y*¹ for the first indicator, and associated with each pair of indication relays is a transfer relay *L* having a corresponding number. Each transfer relay serves to prevent further operation of its indicator after an indication has been registered and is stored therein, and also serves to control the transfer of an indication from one indicator to the next 50 55

- preceding indicator when key **KD** is operated. The group of relays associated with track model **V** as herein illustrated are controlled by a polarized relay **P** over line wires **7** and **8**, by means of the manually operable keys **KX** and **KY**, relay **P** being energized by current of one polarity or the other depending upon whether key **KX** or **KY** is operated. In series with relay **P** in the line circuit, but located adjacent the control panel **U** is an indication relay **ER** controlling a lamp **E**. Lamp **E** is lighted whenever one of the control relays **KX** or **KY** is operated provided relay **P** responds to store the indication. When one lamp of each of the three indicators is lighted, no further storage of indications is possible, and the arrangement is such that additional operations of key **KX** or **KY** will be without effect and the control operator will be made aware of this fact by the failure of lamp **E** to become lighted.
- In order to simplify the drawings, I have shown only the terminals of the source of energy for the various relays and lamps, which terminals I have designated by the references **B** and **C** to indicate respectively the supply and common return terminals of the source.
- Assuming the apparatus is in its normal condition with no lamp lighted, all the relays will be deenergized as shown in the drawing, except the transfer relay **L3** of the last indicator, which is normally energized. The pickup circuit for relay **L3** may be traced from terminal **B**, back contacts **4** of relays **Y3** and **X3**, relay **L3**, back contact **3** of relay **P** to the other terminal **C** of the same source. Relay **L3** also has a stick circuit which is the same as the circuit just traced except that it includes its front contact **1** instead of the back contact of relay **P**. It follows, therefore, that relay **L3** is energized only when the indication relays **X3** and **Y3** of the third indicator are released, and can be picked up only when relay **P** is released.
- Assume now that a train destined for point **x** passes point **a** and that the control operator momentarily closes key **KX**. Relays **P** and **ER** become energized over a circuit which may be traced from terminal **B**, front contact **1** of key **KX**, back contact **1** of key **KY**, relay **ER**, line wire **7**, relay **P**, front contact **3** of relay **L3**, line wire **8**, back contact **2** of key **KY**, front contact **2** of key **KX** to the other terminal **C** of the source, whereupon relay **ER** picks up, closing its contact **1** to light lamp **E**, and polarized relay **P** picks up to close its front contacts **1** and **4** and to open contact **3**, and also closes its polar contact **2** to the left, completing a circuit which may be traced either from terminal **B**, over back contacts **4** of relays **Y2** and **X2**, or from terminal **B** over back contact **3** of relay **L2**, and thence over front contact **2** of relay **L3**, front contact **1** and left-hand polar contact **2** of relay **P**, relay **X3** to terminal **C**. Relay **X3** picks up and closes its contact **1**, bridging the contacts of relays **L3** and **P** in the circuit just traced so that relay **X3** when picked up will remain energized irrespective of the condition of relay **P** or of relay **L3**, and will not release until relays **L2** and **X2** or **Y2** are energized. When relay **P** picks up, the closing of its contact **4**, bridges contact **3** of relay **L3** in the line circuit so that relay **P** when picked up will remain energized as long as key **KX** is closed, even though relay **L3** releases. Relay **X3**, by opening its back contact **4**, releases relay **L3**. Since the pickup circuit for relay **L3** includes back contact **3** of relay **P**, it follows that even though relay **X3** becomes released while relay **P** is energized, relay **X3** can

not again be picked up until after relay **P** has been released to pick up relay **L3**, the arrangement being such that relay **X3** can be operated but once for each operation of relay **P** and that neither relay **X3** nor **Y3** can be operated unless both these relays are released and relay **L3** is energized.

When relay **X3** picks up, a circuit is closed from terminal **B**, back contact **4** of relay **Y3**, front contact **4** of relay **X3**, relay **L2**, back contacts **3** of relays **X2** and **Y2** to terminal **C** so that relay **L2** will pick up closing its contact **1** to complete a connection from its right-hand terminal to terminal **C** in multiple with back contacts **3** of relays **X2** and **Y2**. When relay **L2** picks up, a circuit for relay **X2** will be closed which may be traced either from terminal **B**, back contacts **4** of relays **X1** and **Y1**, or from terminal **B**, back contact **3** of relay **L1**, thence over front contacts **2** of relays **L2** and **X3**, relay **X2** to terminal **C**. Relay **X2** upon picking up closes its contact **1** bridging contacts **2** of relays **X3** and **L2** in its pickup circuit so that it will remain energized irrespective of the condition of these relays. Since back contact **4** of relay **X2** and back contact **3** of relay **L2** are now both open, relay **X3** releases, opening the circuit for relay **L2** and if relay **P** is now released also closing the circuit for relay **L3**. When relay **L2** releases and relay **L3** picks up, the pickup circuit for relay **X3** or **Y3** may be closed by again operating relay **P** and it follows, therefore, that a second indication may be stored in relay **X3** or **Y3** of the last indicator as soon as an indication has been transferred to relay **X2** or **Y2** of the next preceding indicator.

When relay **X2** picks up, a circuit for relay **L1** is closed which is similar to the circuit for relay **L2** already described and when relay **L1** picks up, the pickup circuit for relay **X1** is closed which may be traced from terminal **B**, contact **1** of key **KD**, front contacts **2** of relays **L1** and **X2**, relay **X1** to terminal **C**. Relay **X1** upon picking up closes its contact **1** bridging contacts **2** of relays **L1** and **X2** in the circuit just traced so that relay **X1** will remain picked up irrespective of the condition of these relays and can be released only by the operation of key **KD**. Since back contact **4** of relay **X1** and back contact **3** of relay **L1** are now both open, relay **X2** will release and open its front contact **4** so that relay **L1** will release. Relay **L1** upon releasing, closes its back contact **3** to again connect terminal **B** of the source to the circuits for relays **X2** and **Y2** so that a stored indication may be transferred from the third indicator to the second. However, it will be noted that as long as an indication is stored in the first indicator and relay **X1** or **Y1** is energized, relay **L1** will remain deenergized so that the pickup circuit of relay **X1** or **Y1** will remain open and the stored indication can not be interfered with. Each of the indication relays such as **X1** or **Y1** controls a corresponding lamp such as **XE1** or **YE1** in the track model. The circuit for **XE1** may be traced from terminal **B**, over front contact **5** of relay **X1**, lamp **XE1** to terminal **C**, the circuits for the remaining lamps being similar, as is apparent from the drawing. It follows, therefore, that when key **KX** is operated under the conditions assumed, lamps **XE3**, **XE2** and **XE1** will each become lighted in turn but that only **XE1** will remain lighted.

In the foregoing, I have considered only the operation of the relays **X**, but it will be apparent from the drawings that since their circuits are similar, relays **Y** may be operated in precisely the

same manner by closing key KY. Thus, when key KY is closed, current of the opposite polarity is supplied to the line circuit and relay P is energized in the opposite direction to close its polar contact 2 to the right, to complete the pickup circuit for relay Y3.

Assume now that a second train destined for point y passes point a, and that the control operator operates key KY. Relays P, Y3, L2 and Y2 will be successively energized but further progression will be blocked because relay L1 does not pick up. Lamp YE2 will therefore remain lighted to indicate the route for the second train. Assume now that a third train passes point a and that key KX or KY is again operated. Relays P and X3, or Y3, will pick up, but relay L2 does not pick up, and lamp XE3 or YE3 will remain lighted to indicate the route for the third train. Relay L3 now does not pick up when relay P is released, and the line circuit is held open so that further operation of key KX or KY is without effect and lamp E does not become lighted when these keys are operated, as long as an indication is stored in the third indicator.

Assume now that the first of the three trains occupying the stretch a—b passes the switch W and that the operator at station D presses key KD to release X1 and extinguish lamp XE1. Since relay Y2 is energized, the closing of back contact 3 of relay X1 will cause relay L1 to pick up, and when key KD is released, the pickup circuit for Y1 will be closed to pick up that relay thereby transferring the route indication stored in the second indicator to the first indicator so that lamp YE1 will become lighted. Relays L1 and Y1 now being energized, the stick circuit for relay Y2 of the next succeeding indicator is open so that relay Y2 releases and this in turn causes relay L1 to release. If relay X3 or Y3 is picked up, the release of relay Y2 will cause relay L2 to pick up and when relay L1 releases, the closing of its back contact 3 will complete a circuit to transfer the indication stored in the third indicator to the second, and relay X3 or Y3 and then relay L2 will release, and relay L3 will pick up. There are now two trains remaining in stretch a—b and their route indications are stored in the first and second indicators respectively, and the third indicator has become available for registering the route to be taken by a following train.

Assume now that key KD is operated as the first of these two trains passes switch W. The route indication stored in the first indicator will be cancelled, and when key KD is released, the indication stored in the second indicator will be transferred to the first, as before. Another operation of key KD will cancel this indication and when key KD is restored, the apparatus will be in its original condition.

In order to simplify the drawings, I have shown but three indicators each of which provides but two indications, but the number of indicators may be readily increased and the chain of relays extended to any desired length by merely inserting in the chain additional groups of relays each of which are similar to and are connected into the circuits in the same manner as the relays L2, X2 and Y2 of the second indicator. In practice, the number of indicators employed will generally be more than three, since it is desirable to provide a number of indicators equal to the maximum number of trains that can occupy the stretch a—b at any one time, and point a may be at a considerable distance from

point b. Furthermore, each indicator may readily be modified to provide more than two indications by merely providing each indicator with additional X and Y relays, each indicator requiring but one L relay irrespective of the number of indication relays, and by providing a relay P or an equivalent remote control means for each pair of indications. When arranged to provide additional indications the apparatus of my invention is particularly adapted for use as an annunciator of the approach of trains to a large railway terminal station, to facilitate the switching of the trains to the proper terminal tracks, and when so employed the number of different indications controlled by each indicator will, in general, be equal to the number of terminal tracks in the station.

Referring now to Fig. 2, the polarized relay P and the three groups of relays X, Y and L function in precisely the same manner as in Fig. 1, but relays X1 and Y1 of the first indicator automatically control the operation of a power switch machine SM for operating the track switch W, and no operator is needed at point a. The usual detector track circuit T having a track relay TR is provided for the track section containing the switch and the switch machine is provided with the usual polarized control relay WR having a circuit including a front contact 2 of the track relay so that the switch can not be operated when a train is occupying the detector section. The local circuits for the switch machine have been omitted as these are well known in the art and form no part of the present invention, but they may be arranged, for example, as shown in the Willard Patent No. 1,380,452, issued June 7, 1921. The switch control relay WR is controlled by the relays of the first indicator in such a manner that if the section T is unoccupied, the switch will be operated to normal when relay X1 is energized to permit a train movement from point b to point x and will be reversed when relay Y1 is energized to permit a train movement from point b to point y. In Fig. 2, the release key KD of Fig. 1 has been replaced by a front contact 1 of track relay TR, so that the indication stored by relay X1 or Y1 is released automatically as soon as the train enters section T to pass over the switch and relay X1 or Y1 is again rendered available to register the route to be taken by a following train as soon as the first train passes out of the switch section. Relays X1 and Y1 control indication lamps XE1 and YE1, as in Fig. 1, and associated with these lamps is a pair of manually operable keys KX1 and KY1 by means of which the train crew of an approaching train may operate the switch to change the route if they so desire, as would be the case, for example, if an error has been made in setting up the route.

The pickup circuits for relays X1 and Y1, in Fig. 2, include the front contact 1 of the track relay AR of an approach section A adjacent section T, and a signal S is provided at the entrance to section A. It is to be understood that signal S is controlled automatically in the usual manner to indicate the position of switch W, and that signal S indicates stop when section A or section T is occupied. The arrangement is such that the switch can not be operated by remote control after a train has passed the signal and occupies section A or section T.

Assuming that the indicators have been operated as already described in connection with Fig. 1, up to the point where relays X2 and L1 have become energized, if sections A and T are

unoccupied, the pickup circuit of relay X_1 will be closed, which may be traced from terminal B, front contacts 1 of relays TR and AR, front contacts 2 of relays X_2 and L_1 , relay X_1 to terminal C. When relay X_1 picks up, its stick circuit becomes closed, which circuit may be traced from terminal B, front contact 1 of relay TR, back contact 6 of relay Y_1 , front contact 1 and winding of relay X_1 to terminal C. Lamp X_E now becomes lighted, relays X_2 and L_1 release in sequence, and the normal circuit for relay WR becomes closed. This circuit may be traced from terminal B, front contacts 2 of relays X_1 and TR, relay WR, back contact 2 of relay Y_1 to terminal C, so that relay WR becomes energized in the normal direction, as shown in the drawings, and energizes the switch machine SM to operate switch W to normal. The pickup circuit by which relay Y_1 is controlled by relay Y_2 is similar to the pickup circuit of X_1 but includes front contact 4 of relay L_1 , and relay Y_1 has a stick circuit similar to that of relay X_1 and when energized closes the reverse circuit of relay WR to cause switch W to be reversed, as is apparent from the drawings.

Assuming now that the approaching train occupies section A but not section T, and that the train crew operate key KY_1 . Relays AR and L_1 now being deenergized, an auxiliary pickup circuit for relay Y_1 will be closed which may be traced from terminal B, front contact 1 of relay TR, back contact 1 of relay AR, key KY_1 , back contact 4 of relay L_1 , relay Y_1 to terminal C, so that relay Y_1 picks up, opening its back contact 6 in the stick circuit of relay X_1 . Relay X_1 therefore releases and by closing its back contacts 6 and 2 establishes the stick circuit for relay Y_1 , and completes the reverse circuit for relay WR, so that the switch will be operated to reverse. Relay X_1 may similarly be picked up by closing key KX_1 to operate the switch to normal, as is apparent from the drawings.

When the train passes over the switch the pickup and stick circuits of relays X_1 and Y_1 are opened by contact 1 of relay TR, and if a route indication is stored in the second indicator, relay L_1 will pick up as soon as relay X_1 or Y_1 releases, and as soon as the train leaves section T the closing of contact 1 of relay TR will cause the transfer of the route indication to the first indicator, and relay WR will become energized to operate switch machine SM as already described, so as to set up the route for the next train.

The apparatus at the control station O is also arranged differently in Fig. 2, in order to provide an arrangement which insures positively that but one route indication will be registered for each train. To accomplish this result, a short track section OA is provided adjacent point a, having a track relay OAR which must be released to render key KX or KY operative, and these relays are each provided with a relay XR or YR . In Fig. 2, relay P is energized in series with relay XR when key KX is operated, and in series with relay YR when key KY is operated, provided relay L_3 is energized and a train is occupying section OA. Relays XR and YR are stick relays and remain energized to hold the line circuit closed until the train moves out of section OA, and until this occurs render the circuits controlled by keys KX and KY non-responsive to further operation of these keys.

Assuming that key KX in Fig. 2 is closed, and that section OA is occupied, the normal circuit

for relay P will be completed and may be traced from terminal B, back contact 2 of track relay OAR, key KX , relay XR , back contact 2 of relay YR , line wire 1, relay P, front contact 3 of relay L_3 , line wire 8 to the other terminal C of the source. When relay XR picks up it closes its contact 1 bridging key KX so the circuit will remain closed until track relay OAR picks up, since, as in Fig. 1, when relay P picks up, it closes its front contact 4 to maintain the line circuit closed after relay L_3 releases. The reverse circuit for relay P is similar but includes key KY and relay YR and receives energy over back contact 1 of relay OAR from a terminal N which is connected to terminal C through a source of energy of the opposite polarity to that connected between terminals B and C. Lamp E, which functions in the same manner as in Fig. 1, becomes lighted when either relay XR or YR is energized to close its front contact 3, as is apparent from the drawings.

The control apparatus at station O in Fig. 2 is wholly interchangeable with that of Fig. 1, and may be used to control the track model of Fig. 1. Likewise the indications of the track model may be cancelled by the movement of trains past point b in Fig. 1 in the same way as in Fig. 2, as is obvious.

The apparatus of Fig. 2 is adapted not only to the control of main line train movements, but is equally suited to control the switching of cars in classification yards, where it is the practice to assign a particular route to each car as it passes a control point and then to operate one or more switches to direct the car to the desired terminal track.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In a signaling system, a series of indication relays, control means for at times energizing the last relay of said series, a series of transfer relays including one for each remaining relay of said series, a pickup circuit for each transfer relay including a back contact of the associated indication relay and a front contact of the next succeeding indication relay of the series, a stick circuit for each transfer relay including its own front contact and a front contact of said succeeding indication relay, a pickup circuit for each indication relay except the last including front contacts of the associated transfer relay and of the next succeeding indication relay of the series, a stick circuit for each indication relay except the first including its own front contact and, in multiple, back contacts of the next preceding indication relay of the series and of the transfer relay associated therewith, a release contact, a stick circuit for the first indication relay of the series including its own front contact and said release contact, and indication means controlled by said first indication relay.

2. In a signaling system, a series of indication relays, a series of transfer relays including one for each indication relay, a control relay, a pickup circuit for the last transfer relay of said series including back contacts of the control relay and of the last indication relay, a stick circuit for said transfer relay including its own front contact and the back contact of the last indication relay, a pickup circuit for the last indica-

tion relay including front contacts of the control relay and of the last transfer relay, a pickup circuit for each remaining transfer relay including a back contact of the associated indication relay and a front contact of the next succeeding indication relay of the series, a stick circuit for each said remaining transfer relay including its own front contact and a front contact of said succeeding indication relay, a pickup circuit for each indication relay except the last including front contacts of the associated transfer relay and of the next succeeding indication relay of the series, a stick circuit for each indication relay except the first of the series including its own front contact and, in multiple, back contacts of the next preceding indication relay of the series and of the transfer relay associated therewith, a release contact, a stick circuit for the first indication relay of the series including its own front contact and said release contact, and indication means controlled by said first indication relay.

3. In a signaling system, a series of indication relays, control means effective when operated for at times energizing the last relay of said series, a series of transfer relays including one for each remaining relay of said series, an energizing circuit for each transfer relay closed only when the associated indication relay is released and the next succeeding indication relay of the series is energized, an energizing circuit for each indication relay except the last closed only when its transfer relay and the next succeeding indication relay of the series are energized, means rendered effective when an indication relay and its transfer relay are both energized for releasing in sequence the succeeding indication relay and said transfer relay, means preventing the reenergization of the last indication relay until the control means is again operated, means independent of said relays for releasing the first indication relay of the series, and indication means controlled by said first relay.

4. In a signaling system, a series of relay groups each including a plurality of indication relays, a series of transfer relays including one for each group except the last, a pickup circuit for each transfer relay closed when all the indication relays of its group are released and an indication relay of the next succeeding group is energized, a stick circuit for each transfer relay effective to maintain it energized until such energized indication relay is released, means for energizing a selected indication relay of the last group, means effective when each transfer relay is energized to energize that indication relay of its group which corresponds to the energized indication relay of the next succeeding group, a stick circuit for each indication relay for maintaining it energized until released, means effective when an indication relay and the transfer relay for the same group are both energized to release the energized indication relay of the next succeeding group, means for releasing the energized indication relay of the first group.

5. In a signaling system, a series of indicators each adapted when operated to store a selected indication, a series of transfer relays including one for each indicator except the last of the series, a pickup circuit for each transfer relay closed only when the corresponding indicator is released and the next succeeding indicator is operated, a stick circuit for each transfer relay which becomes effective when it picks up to hold it energized until the next succeeding indicator is energized.

is released, means for operating the last indicator of the series, means effective when each transfer relay is energized to transfer to its indicator the indication of the next succeeding indicator of the series, means effective when any indicator except the last is operated to release the next succeeding indicator of the series, and means for releasing the first indicator of the series.

6. In a signaling system, a series of indicators, each adapted when operated to store a selected indication, a series of transfer relays, including one for each indicator, a pickup circuit for each transfer relay except the last of the series closed only when the corresponding indicator is released and the next succeeding indicator is operated, a stick circuit for each transfer relay except the last which becomes effective when it picks up to hold it energized until the next succeeding indicator is released, control means for operating the last indicator effective only when the last transfer relay is energized, a pickup circuit for the last transfer relay closed only when the control means and the last indicator are both released, a stick circuit for the last transfer relay which becomes effective when it picks up to hold it energized until the last indicator is operated by said control means, means effective when each remaining transfer relay is operated to transfer to its indicator the indication of the next succeeding indicator of the series, means effective when any indicator except the last is operated to release the next succeeding indicator of the series, and means for releasing the first indicator of the series.

7. In combination with a stretch of railway track, a track circuit at one end of the stretch having a track relay, a track switch at the other end of the stretch, a route indicator adjacent the switch for indicating the routes to be taken by trains which have passed over said track circuit and are approaching the switch, manually operable contacts and a stick relay adjacent said track relay, a line circuit including said manually operable contacts and said stick relay and extending to the other end of the stretch, means responsive to the closing of said line circuit to operate said route indicator and said stick relay, means preventing the closing of said line circuit except when the track relay is released, and means controlled by the stick relay when energized to maintain the line circuit closed as long as the track relay remains deenergized irrespective of further operation of said manually operable contacts.

8. In combination with a stretch of railway track, a track circuit at one end of the stretch having a track relay, a track switch at the other end of the stretch, a route indicator adjacent the switch for indicating the routes to be taken by trains which have passed over said track circuit and are approaching the switch, manually operable contacts and a stick relay adjacent said track relay, a line circuit including said manually operable contacts and said stick relay and extending to the other end of the stretch, means responsive to the closing of said line circuit to operate said route indicator and said stick relay, means preventing the closing of said line circuit except when the track relay is released, means controlled by the stick relay when energized to maintain the line circuit closed as long as the track relay remains deenergized, and a visual indicator controlled by the stick relay and indicating when the line circuit is closed.

9. In combination with a railway track switch,

5 a normal control relay and a reverse control relay
for controlling the switch, a stick relay, remotely
controlled means effective only when said control
relays are both deenergized to pick up said stick
relay, means effective when said stick relay is
energized to energize a selected one of said control
relays in accordance with the condition of
said remotely controlled means and to then re-
lease said stick relay, means controlled by the
10 selected control relay to operate the track switch,
and means responsive to the movement of a
train over the switch to release the selected control
relay.

10. In a signaling system, a series of normally
15 deenergized indicators, each adapted when energized
to store a selected one of a plurality of different
indications, control means for selectively energizing
the last indicator of the series to store a selected
indication therein, said control means
20 being manually operable only when one or more
of said indicators are normal, transfer means for
each indicator except the first of the series for
transferring the indication stored therein to the
next preceding indicator of the series, each said
25 transfer means being effective only when such
preceding indicator is normal, means controlled
by each transfer means for restoring the associated
indicator to normal when the next preceding
indicator becomes energized, means effective
30 upon restoration of the last indicator to normal
for preventing further operation of said indicators
until after said control means has been manually
restored to normal, and means for restoring
the first indicator of the series to normal.

35. 11. In combination, a detector section of rail-
way track including a track switch, an approach
section adjacent said detector section, a power
switch machine for operating the switch, a series
40 of indicators each comprising relay means
adapted to be energized in a particular arrangement
for each position of the track switch, manually
operable means for energizing the last indicator
of the series to register a control for the
45 track switch, transfer means associated with
each indicator except the last of the series and
responsive to the release of such indicator to au-
tomatically energize it in accordance with the
condition of energization of the next succeeding
50 indicator of the series and to then release such
succeeding indicator, means preventing the ener-
gization of the first indicator of the series except
when said detector section and approach section
are both unoccupied, means for controlling the
55 switch machine in accordance with the condition
of energization of said first indicator, and means
for releasing said first indicator when the de-
tector section becomes occupied.

12. In combination, a detector section of rail-

way track including a track switch, an approach
section adjacent said detector section, a power
switch machine for operating the switch, relay
means adapted to be energized in a particular
arrangement for each position of the track switch,
manually operable remote control means for en-
ergizing said relay means to register a control for
the track switch, means preventing the energiza-
tion of said relay means by said remote control
means except when the detector section and ap-
proach section are both unoccupied, manually op-
erable means adjacent the track switch for en-
gaging said relay means when the approach sec-
tion is occupied and the detector section is un-
occupied, means for controlling the switch ma-
chine in accordance with the condition of en-
ergization of said relay means, and means for re-
leasing said relay means when the detector sec-
tion becomes occupied.

13. In combination, a detector section of rail-
way track including a track switch, an approach
section adjacent said detector section, a power
switch machine for operating the switch, relay
means adapted to be energized in a particular
arrangement for each position of the track switch,
manually operable remote control means for en-
ergizing said relay means to register a control for
the track switch, means preventing the ener-
gization of said relay means by said remote control
means except when the detector section and ap-
proach section are both unoccupied, manually op-
erable means adjacent the track switch effec-
tive only when the approach section is occupied to
change the condition of energization of said relay
means, means for controlling the switch machine
in accordance with the condition of energization
of said relay means, and means for releasing said
relay means when the detector section becomes
occupied.

14. In a signaling system, a series of indication
reays, a series of transfer relays including one
for each indication relay except the last of the
series, a pickup circuit for each transfer relay
closed only when the corresponding indication
relay is released, a stick circuit for each transfer
relay which becomes effective when it picks up
to hold it energized until the next succeeding
indication relay is released, means for energizing
the last indication relay of the series, means ef-
fective when each transfer relay is energized to
energize the corresponding indication relay pro-
vided the next succeeding relay of the series is
energized, means effective when any indication
relay except the last becomes energized to release
the next succeeding indication relay of the series,
and means for releasing the first indication relay
of the series.
